L. J. CARL

AUTOMOBILE TOP

Filed Oct. 9, 1922

Fig. II.

Figs. 3.

Louis J. Carl, Inventor.
Miller, Henry & Boykin, Attorneys.

UNITED STATES PATENT OFFICE.

LOUIS J. CARL, OF SAN FRANCISCO, CALIFORNIA.

AUTOMOBILE TOP.

Application filed October 9, 1922. Serial No. 593,226.

To all whom it may concern:

Be it known that I, LOUIS J. CARL, a citizen of the United States, and resident of the city and county of San Francisco, State 5 of California, have invented new and useful Improvements in Automobile Tops, of which the following is a specification.

My invention has for its object the enclosing of the upper part of an automobile 10 body including slideable windows on the sides thereof and is particularly directed to the securing of simple and efficient operation of the said windows without sticking or rattling and also the means and 15 mechanism by which the said windows are locked in any position to which they may be adjusted by the operator. Other objects are the securing of more complete vision through the sides, whether the windows are 20 open or closed.

Another object is cheapness and simplicity of construction.

Other objects appear from the drawings and specification which follow.

These objects I accomplish by introducing above the slideable sash or glass plate, described below, a grooved member, movable in a vertical plane and a plurality of wedges adapted to act against said movable 25 member and force it downward and thereby lock the sash; or when the wedges are relieved to permit the sash to slide freely in said grooved member. The sash themselves may consist preferably of plates of glass 30 without wooden frame although the conventional wood frame sash may be employed if preferred. On the body portion of the automobile and corresponding with the lower edge of the sash I introduce other co-operating tongues and grooves, or where the glass plate alone is used in lieu of the conventional sash, the edge of the glass plate is 35 slideable in the grooves at both top and bottom and at least one of the groove members is of elastic, fibrous or rubber material. The tongue is preferably of the glass plate, or if the sash is framed then of fibroid or hard rubber whereby the rusting of the parts together, as well as rattling, is entirely obviated, there being a sufficient elasticity between the two members between 40

the tongue and groove at both top and bottom to permit of slight compression and a secure gripping of the tongue and the groove when the wedges are compressed. 55

By referring to the accompanying drawing my invention will be made clear.

Fig. 1 is a side view of an automobile having my top mounted thereon with a portion of the side removed to better illustrate 60 the operating mechanism.

Fig. 2 is a perspective view of the wedging mechanism and top vertically movable groove member. 65

Fig. 3 is a detail section of the rear end of the groove strip and associated wedge.

Fig. 4 is similar to Fig. 3 of the opposite end of the said strip and mechanism.

Fig. 5 is a cross section on the line V—V 70 of Fig. 3 the section being extended into the body of the automobile.

Fig. 6 is an enlarged cross section on the line VI—VI of Fig. 4 and the section being extended through the lower groove member 75 and a portion of the body of the automobile.

Fig. 7 shows in section an alternate and preferred form of channel strip for lining the grooves. 80

Throughout the figures similar numerals refer to identical parts.

The numeral 1 indicates the body of a conventional automobile on which is constructed my top 2 having an outer depending wall 3 and an inner removable depending wall 4. It is to be understood that these walls are located on each side of the automobile right and left. The walls 3 and 4 are bound together against the edge member 90 5, and wall 4 preferably by the screws 6, 6, so that it may be readily removed to gain access to the mechanism described below. 85

Between the walls 3 and 4 and below 95 member 5 is a channel shaped space within which is mounted the vertically movable strip 7, kept in position and from end-wise movement by the screws 8, 9, fastened in the edge member 5 and having heads to hold the strip 7 but permitting its free vertical movement on the shanks of the said 100

screws and being suitably countersunk for covering the heads of the said screws.

On the groove strip 7 are mounted the wedge shaped blocks 10, 11, and adapted to 5 cooperate therewith are the wedges 12, 13, slideable right and left in the direction of the length of the strip 7 when the handle 14 is moved into the dotted position of Fig. 2, at which time the wedges force the blocks 10, 11, away from the edge strip 5 and therefore force downward the vertical movable groove strip 7 gripping tightly the sash between the strip 7 and the track member 15 mounted on the body of the vehicle 1.

15 When the handle 14 is withdrawn from the dotted position into the full line position of Fig. 2 the wedges 12, 13, disengage from the blocks 10, 11, and the strip 7 is relieved of pressure against the 20 sash which may then be slid freely backwards or forwards into any desired position under the friction only due to the weight of the sash and the strip 7. The sash I prefer to form of a single plate of 25 glass 16 having ground and finished edges and holes or suitable finger members cemented thereon as at 18, whereby the said glass plate may be shifted back and forth in the grooves 19, 20, or 21, 22. These 30 grooves are preferably provided with a rubber or rubber composition or felt lining as shown at 23, 24, 25, 26, respectively, 23, 25, being fixed in the strip 7, and 24, 26, in the body edge 15.

35 Or if preferred, the conventional wood frame sash as shown at 27, 27, Fig. 4, may be employed in which case I prefer to line the grooves in the strips 7, 15, with aluminum, brass or other suitable non-rustable 40 metal as shown at 28, 29, and 30, 31. The sash tongues shown at 32 I prefer to make of brake lining material or other closely woven and treated fibre which is fixed in the sash frame 27 along its lower edge, and 45 in the upper portion of the said sash frame.

27 I provide a similar tongue preferably made of rubber 33, although other material may be employed if preferred. The usual plate glass is also fitted to this sash 50 as shown at 34. The frame 27 is made to clear the strips 7, 15, the tongues 32 and 33 seating in the bottom of the grooves of the members 28, 29, respectively, so that the edge of the sash does not rub against or otherwise damage the vehicle finish.

Whichever form of sash is employed I provide in the tongue and groove members at the top and bottom of each sash one relatively hard rigid material either as the 60 tongue or lining of the groove and a second relatively elastic material as the lining of the groove or tongue, respectively, thus where glass plates are employed as 16 without the wooden sash, the glass is the relatively rigid or hard material and the felt

or rubber lining as 23, 24, 25, or 26 is the relatively elastic material as shown in Fig. 5; whereas when wooden frame sash are employed as shown in Fig. 6 the fibre or brake lining material 32 and rubber 33 forming the tongues at the bottom and top respectively are relatively elastic and the metal lining 28, 29, is relatively rigid. In this type of sash the strip 7 is adapted to move vertically compressing the elastic member sufficiently to hold the sash rigidly in place by friction and to prevent its rattling through the action of the wedges 12, 13, acting upon the blocks 10, 11. The handle is pivoted at 40 to the strip 5 and carries the arm 41 pivoted at 42 controlling the wedge 12, and the arm 43 pivoted at 44 controlling the wedge 13. The handle 14 passes through a slotted opening 45 in the removable side wall 4, and a suitable trim plate 46, makes a finished opening through which the handle projects into the body of the vehicle immediately under the top 2 and in a convenient location to be operated from the inside. It will now be seen that by removing the screws 6 the removable wall 4 may be readily taken out when the lever 14 and its associated wedges and operating mechanism and the strip 7 and window sash removed, repaired or adjusted as may be desired.

The metal strips that are shown lining the grooves 28, 29, 30, 31, may be pressed or rolled from sheet metal and I prefer aluminum for this in which case the edges are preferably turned over as shown in Fig. 7, also it is to be understood that the parts are to be suitably lined as with any suitable upholstering material not shown but by which the excess clearance spaces between the strip 7 and walls 3 and 4 is reduced to a suitable working fit. Such variations will readily occur to one skilled in the art and I wish to be understood as claiming all such.

I claim:

1. In an automobile a plurality of windows, a strip having channel ways movably suspended in the top and other channel ways in the body portion of the automobile, a plurality of wedge couples by which said strip may be forced downward and connections including a handle for operating said wedge couples to depress the strip and clamp the windows between the channel ways in any of their adjusted positions, said windows comprising glazed sash having flexible tongues at the top and bottom adapted to engage the channel ways.

2. In an automobile a plurality of windows, a strip having channel ways movably suspended in the top and other channel ways in the body portion of the automobile within which channel ways said windows are adapted to travel horizontally, a plurality of wedge couples by which said strip

may be forced downward and connections including a handle for operating said wedge couples to depress the strip and clamp the windows between the channel ways in any 5 of their adjusted positions and outside and inside walls depending from said top and forming therebetween an operating space

for said strip, said windows comprising glazed sash and said sash are provided with rubber fibroid tongues at the top and bottom respectively adapted to engage the 10 channel ways.

LOUIS J. CARL.
